UNITED STATES PATENT OFFICE.

LOUIS STEINBERGER, OF BROOKLYN, NEW YORK.

STRAIN-INSULATOR.

1,205,812.

Specification of Letters Patent. Patented Nov. 21, 1916.

Application filed November 24, 1913. Serial No. 802,686.

To all whom it may concern:

Be it known that I, LOUIS STEINBERGER, residing at Brooklyn, in the county of Kings and State of New York, have invented certain new and useful Improvements in Strain-Insulators, of which the following is a specification.

This invention relates to strain insulator constructions such as are used for high tension currents.

The principal object of this invention is to improve the construction and efficiency of insulators of this type.

A further object is to improve the construction of the strain members so that a series of insulators of the type disclosed may be connected in chain relation without the interpositioning of special connecting members.

20 A further object is to provide a two-part strain member and means for connecting the parts thereof together, and to so dispose a portion of the insulator structure as to positively indicate when the parts of the 25 strain member are properly assembled.

Other objects and aims of the invention, more or less specific than those referred to above, will be in part obvious and in part pointed out in the course of the following 30 description of the elements, combinations, arrangements of parts and applications of principles, constituting the invention; and the scope of protection contemplated will be indicated in the appended claims.

35 In the accompanying drawings which are to be taken as a part of this specification, and in which I have shown a merely preferred form of embodiment of the invention: Figure 1 is a transverse, central, sectional view through an insulator constructed in accordance with the provisions of this invention: Fig. 2 indicates a pair of insulators constructed substantially as in Fig. 1 arranged in concatenated relation, the upper 40 insulator unit being shown in transverse section on a plane at right angles to the plane of the section shown in Fig. 1; and Fig. 3 is a bottom plan view, on a slightly reduced scale, of the structure shown in 45 Fig. 1.

50 Referring to the drawings for a detailed description of the structure illustrated, the

reference character L indicates generally the disk portion of the insulator. This may be of any preferred shape or design but is 55 necessarily formed with a central or body portion 1, of sufficient bulk to receive and retain, with ample mechanical strength, the opposite strain members.

The strain members are indicated by reference characters G and H. The strain member G is of two parts as 2 and 3. The part 2 comprises a U-shaped metallic member having the greater portion of its length embedded and concealed within the material of the body portion 1 of the disk. The opposite ends of the legs of the U project beneath the lower surface of the body and are threaded for the attachment of the separately formed U-shaped part 3 which cooperates with the embedded part 2 to complete therewith a closed link. The part 3 has its opposite legs disposed with their ends abutting the projecting ends of the legs of the part 2. These legs may be connected 70 in any approved manner but are preferably connected by the means shown, which connecting means is specifically claimed in my co-pending application. This connecting means consists in a threaded socket 4 upon 75 one leg of the part 3, for engagement with the threads of the adjacent leg of the part 2 by bodily inter-rotation between said parts, and in a separately formed sleeve 5 engaging threads upon the other leg of the part 80 3, and extending into engagement with the threads of the adjacent leg of the part 2. The sleeve is rotatable to travel along the leg of the part 3, to free itself from engagement with the threads of the part 2, so that 85 the part 3 may be rotated bodily as suggested. The other strain member, as H, may be a two-part structure as just described for the strain member G, or it may be formed as a solid closed link as shown at the bottom 90 of Fig. 2, according to convenience or requirements.

Strain insulators, as heretofore manufactured with closed eyes or loops and the like projecting from opposite sides thereof, have 100 required the use of a separately formed connecting member for joining adjacent units together. By providing the strain members with means whereby the eyes or loops may

be opened, as herein suggested, it is apparent that adjacent insulators may be directly connected with each other, as shown in Fig. 2, without the provision and interposition of the separately formed connecting members. The strain members themselves fulfil the requirements and economize space and material and greatly facilitate the work of the operator. The cost of production, considering the reduced weight of metal required, is little if any more than the cost of suspension members requiring the use of separately formed connecting members. In the use of the device, and in the making of repairs, alterations, etc., there is little or no likelihood of the connecting means being mislaid or lost, or of the supply thereof giving out, as is frequently the case when separately formed connecting members are employed.

20 The disk portion L of the structure is preferably formed of insulating material such as "electrose" and may be provided with any suitable form of protection parts 6, as desired.

25 The several units which may be connected for completing a chain type insulator may be of uniform size and insulating qualities, or they may be graded relatively to each other as suggested by the difference in diameter between the two disks shown in Fig. 2, if desired.

It may be particularly noted that the sleeves 5 are preferably of a length substantially equal to twice the length of the projecting threaded portion of the part 2, and that suitable bosses or projections 7 are formed upon the insulator body so as to provide flat abutting surface for the ends of the sleeves to positively limit the travel of 35 the sleeves upwardly upon the threaded portions of the part 2.

40 indicates a brace formed preferably of a stiff metal, each end of which is provided with suitably formed portions to engage 45 with the legs of the suspension members. This brace may extend exteriorly of the insulator or may be set into the material of the insulator as shown in the lower insulator of Fig. 2. In some instances the brace may 50 form an integral part of the suspension members.

The upward travel of the socket 4 is limited in like manner, and by this means it is apparent that an operator is merely to 55 adjust the socket and the sleeve until engagement is made with the bosses 7 when he is assured that the desired accurate adjustment has been obtained.

60 As many changes could be made in the above described construction, and various embodiments of the invention could be made without departing from the scope thereof, it is intended that all matter contained in the above description, or shown in the accom-

panying drawings, shall be interpreted as 65 illustrative only, and not in a limiting sense, and that the following claims are intended to cover all the generic and specific features of the invention which may be said to fall within the language of said claims. 70

Having thus described my invention what I claim as new and desire to secure by Letters Patent, is:

1. An insulator formed of a body portion of insulating material, a member partly embedded therein and having a portion projecting from said insulating material, a member to be connected to said projecting portion, a threaded sleeve rotatably mounted on said member, said projecting portion being threaded to be engaged by the threads of said sleeve, and said body of insulating material having a part disposed to be engaged by said sleeve for limiting the travel of said sleeve along the threads of said projecting portion for the purpose set forth. 75

2. A disk type strain insulator comprising a disk of insulating material, a strain member embedded partly within said insulating material and having threaded portions projecting from said insulating material in spaced relation, a U-shaped member disposed with its two legs arranged to abut the projecting portions of said strain member, threaded parts carried by each of the legs 90 of said U-shaped member for engaging the threads of the projecting portions of said strain member, and the disk of insulating material being provided with parts disposed for limiting the travel of said threaded parts 100 upwardly upon the projecting portions of said strain member for the purpose set forth.

3. An insulator formed of a body of insulating material, a member partly embedded therein having a threaded portion projecting beyond one surface of said body of insulating material, a second member to be connected to said projecting portion, said second member having threads formed on 105 one end thereof, said end being adapted to be disposed in alignment with the projecting portion of said embedded member, so that the threads thereof will form a continuation of the thread of said projecting portion, a 110 separately formed threaded sleeve engaging the threads of said second member being freely movable longitudinally therealong and onto the threads of the projecting portion of the first member, and the body of insulating material being formed with a part disposed to arrest the longitudinal movement of said sleeve when said sleeve is substantially equally in engagement with the threads of said first and said second members. 115

4. A strain insulator, comprising a body portion of insulating material, a pair of

strain members partly disposed within said body portion and insulated from each other, one of said strain members comprising a **U**-shaped portion having the ends of its two legs extending from said insulating material, a strengthening member engaging the extending portion of the legs of said **U**-shaped portion, means engaging said ends of

said legs to form a closed loop, and means whereby said loop may be opened.

In testimony whereof, I affix my signature in the presence of two witnesses.

LOUIS STEINBERGER.
